DESIGN FOR A BOTTLE CAP

Elno H. Trump, Barberton, Ohio, assignor to Plastic Engineering, Inc., Cleveland, Ohio, a corporation of Ohio

Application April 24, 1943, Serial No. 110,035

Term of patent 7 years

To all whom it may concern:

Be it known that I, Elno H. Trump, a citizen of the United States and a resident of Barberton, Summit County, Ohio, have invented a new,
original, and ornamental Design for a Bottle Cap, of which the following is a specification, reference being had to the accompanying drawing, forming a part thereof.

In the drawing:

Figure 1 is a side elevational view of a bottle cap showing my new design, and Figure 2 is a plan view of the bottle cap of Figure 1.

I claim:

The ornamental design for a bottle cap, as shown.

E. H. TRUMP.
